UNITED STATES PATENT OFFICE.

WALTER F. ROPER, OF HOPEDALE, MASSACHUSETTS, ASSIGNOR TO DRAPER COMPANY, OF HOPEDALE, MASSACHUSETTS, A CORPORATION OF MAINE.

SHUTTLE-CHECKING MEANS FOR LOOMS.

SPECIFICATION forming part of Letters Patent No. 761,999, dated June 7, 1904.

Application filed March 7, 1904. Serial No. 196,796. (No model.)

To all whom it may concern:

Be it known that I, WALTER F. ROPER, a citizen of the United States, and a resident of Hopedale, county of Worcester, State of Massachusetts, have invented an Improvement in Shuttle-Checking Means for Looms, of which the following description, in connection with the accompanying drawings, is a specification, like characters on the drawings representing like parts.

This invention has for its object the production of novel means for checking the movement of a loom-shuttle when boxed, whereby a greatly-increased surface friction is attained, with consequent efficiency in the checking action.

The ordinary binder is made as a bar or arm of wood or metal or a combination thereof fulcrumed at the outer end of the shuttle-box and having its contact-face variously shaped to act upon the incoming shuttle.

A binder-spring maintains the binder in position to be struck by the incoming shuttle, and the force of the blow swings the binder outward, while the shuttle continues its movement in the box, and the shuttle may sometimes continue almost to the end of its stroke before being again engaged by the binder as it is moved inward by the binder-spring. At all events the binding or checking action is practically confined to the shoulder of the shuttle during the greater part of the boxing, it being manifest that in consequence only a very limited amount of surface of both shuttle and binder can exert any checking action.

Various constructions have been devised having in view the better and more effective checking of the shuttle, and some of the devices have met with a fair degree of success.

In my present invention I have radically departed from the usual form of rigid inflexible binder and have devised a novel form of flexible binder which is so constructed and arranged that it conforms to the shape of the shuttle as it enters and moves along in the shuttle-box, so that the checking pressure is exerted over quite a large surface.

By the use of such a flexible binder as will be hereinafter described I am enabled to greatly augment the effectiveness of the checking action without the aid of strong controlling-springs, and I can also cause the inner end of the binder to remain in engagement with the shuttle from the instant of impact.

The various novel features of my invention as embodied in one practical form thereof will be fully described in the subjoined specification and particularly pointed out in the following claims.

Figure 1 is a top or plan view of one end of the lay of a loom with the shuttle-box thereon with one embodiment of my novel shuttle-checking means applied thereto, shown in the position assumed when the shuttle-box is empty. Fig. 2 is a similar view, but showing the shuttle boxed and the binder in full co-operation therewith. Fig. 3 is a transverse section on the line 3-3, Fig. 1, looking toward the right; and Fig. 4 is a front elevation of the binder detached.

In Figs. 1 and 2 the cover-plate of the shuttle-box is broken out to more clearly show the binder.

The lay A, picker-stick P, protector rock-shaft H, its controlling-spring H^X, the up-turned binder-finger h^X, having an adjustable contact-stud h, the dagger H², back and front walls b b', and cover-plate b² of the shuttle-box may be and are all of well-known or usual construction, the back wall of the box having a rearwardly-projecting shelf b^X to sustain the inner end of the binder.

In accordance with my present invention the binder as a whole is made flexible in the direction of its length by a species of articulation or jointing in order that it may conform to the shape or contour of the shuttle, and thereby exert an increased and more effective checking action upon the shuttle by reason of the increased friction-surface attained.

Referring to the drawings, the binder comprises a series of contact or binder members c c' to c⁵, preferably made of wood, though any other suitable material may be employed, the

outermost member c being fulcrumed at the outer end of the shuttle-box on the usual stud b^3 . The innermost member c^5 of the series has a prolongation c^6 , which rests upon the 5 projection b^8 and extends back of the box-wall b , the latter limiting inward movement of the binder when the shuttle-box is empty in usual manner. I have provided a common support, connection, and controller for the 10 said binder members, the same consisting of a thin, flat, and elongated strip c^8 of elastic and flexible metal, such as a leaf-spring. This support is extended longitudinally of the series of binder members, the latter being longitudinally notched or grooved, as will be explained, to receive and straddle the support, and referring to Fig. 4 I have shown the end-most members secured to the support by fastenings 2, which may be screws, rivets, or other 15 suitable means, the grooves 1 in said members being just wide enough to snugly receive the support. The binder members are thus articulated or jointed by or through the co-operation therewith of the support c^8 . The 20 outermost member c has an upright hole 3, Fig. 4, to receive the fulcrum-stud b^3 , the members c and c^5 serving to prevent longitudinal displacement of the intermediate binder members on the support c^8 .

25 Referring to Fig. 1, it will be seen that normally the contact-faces of the binder members present a convex surface for the binder as a whole, the face of the member c^5 presenting a shoulder or swell 4 to receive the initial impact of the incoming shuttle. When the 30 box is empty, the contact-face of the binder projects into the path of the shuttle, as is the case with an ordinary rigid binder. The adjacent sides of the different members are concaved from front to rear, as shown at 5, and the grooves 6 in the intermediate binder members c' to c^4 are made with their side walls flared at the ends, as shown by dotted lines, Figs. 1 and 2, so that each member may rock 35 or turn on the support to accommodate itself to the portion of the shuttle-wall opposite thereto when the shuttle enters the box. This individual rocking or turning feature of the binder members, together with the flexibility 40 and resilience of the support and connection c^8 , enables the binder as a whole to bend or flex, and thereby conform to the shape of the shuttle, and by reference to Fig. 2 it will be seen that the contact-surface of the binder has 45 as a whole changed from convex, as when the shuttle-box is empty, to a concave form beyond the member c^5 when the shuttle is boxed. As the shuttle enters the box it strikes the swell 4 of said member c^5 , and the binder as a 50 whole is swung outward on the fulcrum b^3 , the dagger being thereby lifted sufficiently to clear the usual frog (not shown) as the lay beats up. This outward swing is limited, however, by the dagger-stop H^3 , Fig. 3, which is ad-

justably mounted on the lay and adapted to 65 be engaged by the dagger when the protector-shaft H is rocked. In practice this dagger-stop is so set or adjusted that the binder member c^5 can only move outward when struck by the shuttle far enough to permit the passage 70 thereby of the shoulder of the shuttle, said member remaining in contact with and pressing upon the shuttle during boxing thereof, and thereby adding to the checking action of the binder. The resiliency of the support c^8 75 permits one after another of the members c' c^3 , &c., to successively engage the shuttle as it continues its movement in the box, and said members by reason of their flared grooves 6 and convex sides 5 position themselves individually to conform to the particular portion 80 of the shuttle opposite thereto. Thus when the shuttle is completely boxed the binder members will have arranged themselves to conform substantially to the shape of the 85 shuttle, as shown in Fig. 2, and by reference thereto it will be seen that all of the binder members except the outermost one c are in engagement with and pressing upon the shuttle. The binding pressure therefore is exerted upon a comparatively large surface of the shuttle instead of being practically localized near or upon the shoulder of the shuttle.

So far as my invention is concerned or the 90 operation thereof the support may be substantially straight when the shuttle-box is empty, the said support then assuming a concave shape toward the shuttle when the latter is boxed, or said support may be somewhat convexed when the box is empty, becoming 95 more nearly straight when the shuttle is boxed.

The binder members may be faced with leather, if desired, in the manner that ordinary binders are sometimes made.

My invention is not restricted to the precise 105 construction and arrangement herein shown and described, as the same may be modified or rearranged in various particulars by those skilled in the art without departing from the spirit and scope of the invention.

Having fully described my invention, what 110 I claim as new, and desire to secure by Letters Patent, is—

1. In a loom, a shuttle, a shuttle-box, and articulated checking means to act upon and 115 conform to the shape of the shuttle when boxed.

2. In shuttle-checking means for looms, in combination, successively-acting contact or 120 binder members, and a common, elastic controller connected with and supporting the same, whereby said members may accommodate themselves to the shape of the shuttle.

3. In shuttle-checking means for looms, in combination, successively-acting contact or 125 binder members, and an elastic, flexible support therefor.

4. In shuttle-checking means for looms, in

combination, successively-acting contact or binder members, and means to connect them to move bodily in unison while permitting individual movement of said members to conform to the shape of the shuttle when boxed.

5. In shuttle-checking means for looms, an articulated flexible binder to coöperate with and conform to the shape of the shuttle when boxed.

10. 6. In shuttle-checking means for looms, a flexible and elongated elastic support, and successively-acting contact or binder members mounted thereon and adapted to individually position themselves in conformity with the 15 shape of the portion of the shuttle engaged thereby.

7. In shuttle-checking means for looms, a plurality of successively-acting contact or binder members, a flexible and elastic common support and connection therefor permitting individual positioning of said members, and a spring to control the movement of the 20 said members and their support as a whole.

8. In shuttle-checking means for looms, a 25 binder comprising a plurality of contact members, and a flexible, elastic connection therebetween.

9. In a loom, a shuttle-box, a binder fulcrumed at the outer end thereof and comprising 30 a flexible support, a plurality of contact or binder members mounted on said support, and a spring to control bodily movement of the binder due to impact of the shuttle.

10. In a loom, in combination, a shuttle-box, and a binder comprising an elongated flexible 35 and elastic metallic support, and a series of contact or binder members mounted to rock thereon and having their adjacent sides convex to permit individual positioning of said members to conform to the shape of the shuttle 40 when boxed.

11. In shuttle-checking means for looms, a flexible binder comprising a flat and elongated elastic support sustained at its outer end, and a series of contact or binder members longitudinally notched in vertical planes to straddle 45 and be sustained by said support, the adjacent sides of the said members being convex to permit individual positioning thereof.

12. In a loom, a shuttle-box, a flexible binder 50 comprising a flexible, elastic support, a series of contact or binder members mounted thereon and adapted to act successively upon the shuttle during boxing thereof, the innermost member having a convexed face or swell to 55 receive initial impact of the shuttle, and means to act upon said member and maintain it in contact with the shuttle subsequent to initial impact therewith.

In testimony whereof I have signed my name 60 to this specification in the presence of two subscribing witnesses.
